CLAIM

I claim the ornamental design for footwear, as shown and described.

DESCRIPTION

FIG. 1 is a top plan view of footwear.

FIG. 2 is a bottom plan view of the footwear of FIG. 1.

FIG. 3 is an inner side elevation view of the footwear of FIG. 1.

FIG. 4 is an outer side elevation view of the footwear of FIG. 1.

FIG. 5 is a front elevation view of the footwear of FIG. 1; and,

FIG. 6 is a rear elevation view of the footwear of FIG. 1. The broken lines in the figures are for the purpose of illustrating environmental structure and form no part of the claimed design. The dash-dot broken lines in the figures illustrate an unclaimed boundary and form no part of the claimed design.

(Continued)

Any combination of the illustrated features may be claimed in this application or a continuing application claiming priority to this application by converting any of the solid lines to broken lines, any of the broken lines to solid lines, or any combination thereof.
